UNITED STATES PATENT OFFICE

IVAN ROĆIĆ, OF NEW YORK, N. Y.

DESIGN FOR A TABLE OR THE LIKE

Application filed February 15, 1929. Serial No. 30,076. Term of patent 14 years.

To all whom it may concern:

Be it known that I, IVAN Roćić, a citizen of the Kingdom of Croatia, Yugoslavia, and a resident of the city of New York, county of New York, and State of New York, have invented a new, original, and ornamental Design for a Table or the Like, of which the following is a specification, reference being had to the accompanying drawing, forming part thereof.

The Fig. 1 is a top view, Fig. 2, a side view and Fig. 3, a bottom view respectively of a table or the like, showing my new design.

I claim:

The ornamental design for a table or the like, as shown:

IVAN ROĆIĆ.
